Inventors:

United States Patent Office.

SAMUEL HODGINS, OF ST. LOUIS, MISSOURI, ASSIGNOR TO HIMSELF AND SAMUEL B. TUCKER, AND SAID HODGINS ASSIGNOR TO M. JAMES BARWICK, OF SAME PLACE.

Letters Patent No. 67,545, dated August 6, 1867.

SPIRAL FISSURE NEEDLE.

The Schedule referred to in these Letters Patent and making part of the same.

Be it known that I, SAMUEL HODGINS, of the city and county of St. Louis, and State of Missouri, have invented a new and improved surgical needle, known as Hodgins' Spiral Fissure Needle for closing wounds, cleft palates, fissures *in utero*, and fissures *in ano*; and I hereby declare that the following is a full and exact description thereof, reference being had to the accompanying drawings, and to the letters and figures marked thereon.

This invention consists of a wire made from the best of steel, as large as a large curved surgical needle, made solid, hollow, or grooved. The hollow or groove should extend from the eye back towards the haft for impaling the ligature or thread. One end of the wire is shaped as a surgical needle bi-convex, with an eye to secure the ligature at a proper distance back from the point. The other end of the wire contains a screw-socket (marked C) to connect it with the haft or staff. The wire is now bent in the form of a scroll or cork-screw, with as many twists as you wish stitches taken in the fissure or wound, and of such diameter for the scroll of needle as will answer to the depth of the wound.

The scroll on the drawing is marked B, and the point of needle and eye are marked A. The socket-end of the needle is marked C. The ligature is marked A'. The haft or shaft is made of steel, of such size as to give it strength, marked E, with a screw on end, marked D, to fit the socket C. The handle is made of ivory, bone, wood, or metal, marked F, seen at Figure 2.

Figure 1 shows scroll and diameter of needle of three-quarters of an inch.

Figure 3 shows the shaft and handle of the instrument.

Figure 4 shows the diameter of a needle of one and a half inch for deep incisions and wounds; also an enlarged view of point, groove, and eye, with a ligature at A A', and a lateral view of needle, point, and ligature at A A'.

Having thus described my invention, what I claim as new herein, and desire to secure by Letters Patent, is—

1. The spiral fissure needle A B, constructed substantially as and for the purpose herein specified.
2. The combination, with the above, of the haft or shaft E, attached by means of the screw D and socket C, or in any equivalent manner, substantially as described.
